UNITED STATES PATENT OFFICE.

SAMUEL E. MORRAL AND WILLIAM W. MORRAL, OF MORRAL, OHIO.

EAR-REMOVING DEVICE.

Application filed November 12, 1920. Serial No. 423,507.

To all whom it may concern:

Be it known that we, SAMUEL E. MORRAL and WILLIAM W. MORRAL, citizens of the United States, residing at Morral, in the 5 county of Marion and State of Ohio, have invented certain new and useful Improvements in Ear-Removing Devices, of which the following is a specification, reference being had therein to the accompanying 10 drawing.

This invention relates to ear removing devices such as are employed in connection with corn husking machines and the like.

One object of the invention is to provide 15 an ear removing device which will separate the ear from the stalk without crushing or breaking the stalk, thus enabling the stalk to be again placed in a shock; and to this end it is a further object of the invention to 20 provide snapping rollers of special construction which will feed the stalk between the rollers, without crushing it, and snap the ear from the stalk.

A further object of the invention is to 25 provide an ear removing device which will snap the ear from the stalk without shelling the corn from the ear.

It is also an object of the invention to 30 provide suitable means for feeding the stalks to the ear removing devices and properly positioning the ears with relation to such devices.

Other objects of the invention will appear 35 as the mechanism is described in detail.

In the accompanying drawings Fig. 1 is 40 a side elevation of a corn husking machine embodying our invention; Fig. 2 is a rear elevation of such a machine; Fig. 3 is a plan view of the same; Fig. 4 is a transverse sectional view taken centrally through the snapping rollers; Fig. 5 is an enlarged plan view of a portion of one of the snapping 45 rollers; Fig. 6 is a side elevation of a modified form of snapping roller; Fig. 7 is a transverse-sectional view of the roller shown in Fig. 6; Fig. 8 is a transverse sectional view showing a further modified form of snapping roller; and Fig. 9 is a transverse 50 sectional view showing another modified form of snapping roller.

In these drawings we have illustrated one embodiment of our invention, together with certain modifications of the snapping rollers, and have shown the same as forming 55 part of a portable corn husking machine

which is adapted to be coupled with a wagon or the like and moved from shock to shock in the field, the corn in one shock being husked, the stalks returned to the shock and the husking machine then moved to the next 60 shock. The mechanism is of such a character that the stalks will be fed first to the snapping rollers where the ears are removed and the stalks delivered to a pile in the rear of the machine. The ears, as they are removed from the stalks, pass to corn husking devices which remove the husks therefrom and deliver the husked ears to a conveyor which carries them to the wagon or other 65 desired point of delivery. It will be understood, however, that this particular mechanism has been chosen for the purpose of illustration only and that the invention, in its essential characteristics, may be utilized with corn husking devices of various 70 kinds, or if desired, may be used independently of a corn husking device.

In the construction here illustrated the machine comprises a main frame 1 which is preferably mounted on wheels 2 so that it 75 can be readily transported from one point to another. Supported above the frame 1 by standards 3 is a platform consisting of a substantially horizontal portion 4 and an inclined portion 5, the inclined portion sloping downwardly toward the front end of the machine, that is, the end at which the stalks of corn are delivered to the machine and from which they are moved toward the ear removing devices. At its front end the 80 inclined platform 5 is provided with an upwardly extending part 6 which, with the platform, forms a trough in which the corn is piled as it is taken from the shock and from which it is fed toward the horizontal 85 portion 4 of the platform by suitable feeding devices. As here shown, the feeding devices comprise feed chains 7 provided with projections, or cleats, 8, and passing about sprocket wheels secured to shafts 9 and 10, 90 mounted near the front and rear ends of the inclined platform, the sprocket wheels being so arranged that the upper stretches of the feed chains will travel just above the platform. The feeding device may be operated in any suitable manner, but, as here shown, the shaft 9 has secured thereto a worm wheel 11 with which meshes a worm 95 12 carried by a shaft 13 which is driven by means of beveled gearing 14 from a shaft 15 100 105 110

journaled on the standards 3 at the front end of the machine. The shaft 15 constitutes the main driving shaft of the machine and may be driven in any suitable manner, 5 but we prefer that it shall be driven from a motor mounted on the frame of the machine and to this end we have here shown an internal combustion engine 16 mounted on the frame 1 and connected, by means of 10 a belt 17, with the shaft 15.

As the stalks of corn are fed from the inclined to the horizontal platform they are advanced by other means to the snapping rollers. They may be moved into engagement 15 with the snapping rollers in any suitable manner but we prefer to provide power driven mechanism for feeding them forwardly, and, as here shown, we have provided a feeding device comprising feed 20 chains 18 having cleats 19 and extending about sprocket wheels carried by shafts 20 and 21, journaled beneath the platform 4 near the rear and front edges thereof, respectively. The sprocket wheels are so positioned with relation to the platform that the upper, or operative, stretches of the feed chains will be spaced above the platform a distance sufficient to prevent a stalk being moved out of engagement with the cleats if 25 the stalk rides over the ear. The feeding device may be operated in any suitable manner but we have here shown the front shaft 21 as driven by a chain 22 from a shaft 23 journaled on the upright standards 3 at the 30 rear end of the machine and driven from the main driving shaft 15 by a sprocket chain 24. If desired guide arms may also be provided to hold the stalks in engagement with the cleats on the chains and, as here shown, 35 arms 25 are arranged above and spaced a short distance from the feed chains, these arms being rigidly secured to and extending forwardly from a transverse bar 26. Journaled in the front ends of the arms 25 is a shaft 27 having secured thereto a plurality of pin wheels 28 arranged to engage the stalks of corn and positively move them one at a time between the feed chains and the 40 guide arms. These pin wheels may be rotated in any suitable manner but, as here shown, the shaft 27 carries a gear 29 which meshes with a gear 30 on the shaft 21.

The ear removing devices, or snapping rollers, are arranged near the rear end of the horizontal platform 4 and are here shown as spaced a short distance from the rear edge of that platform. The lower roller 31 is carried by a shaft 32 which is driven by a sprocket chain 33 from the shaft 45 23. The upper roller 34 is carried by a shaft 35 journaled on the transversely extending bar 26 and is driven from the shaft 23 in a direction opposite that in which the roller 31 is driven. To this end the shaft 60 23 is connected by means of a sprocket

chain 33^a with a counter shaft 36 which in turn is connected by spur gearing 37 with the shaft 35, which carries the upper snapping roller. The snapping rollers may be of any suitable character but are preferably 70 so constructed and arranged that they will permit the passage of the stalk of corn between the rollers without breaking it, will snap the ear from the stalk, and will not shell the corn from the ears to such an extent as to be seriously objectionable. We have found in practise that snapping rollers of a small diameter are less liable to shell the corn from the ears than are rollers of 75 larger diameters. In order to use the small 80 rollers to snap the ear from the stalk we have found it desirable to so shape, or mount, the rollers that when they are in one position a space or clearance will be provided between them sufficient to permit the 85 passage of the stalk, after which the further rotation of the rollers will cause them to engage the ear and sever the same from the stalk. This may be accomplished in various ways and, by way of illustration, we have shown several shapes and arrangements of snapping rollers which will operate in a satisfactory manner. In that form 90 shown in Figs. 4 and 5 each snapping roller has on one side thereof a circumferentially arranged series of corrugations, or ribs, 38 which extend longitudinally of the roller and are so arranged that the ribs of the two rollers will cooperate to snap the ear from the stalk. Inasmuch as the ribbed portions of the rollers will not satisfactorily feed the stalk between the rollers, in the arrangement shown, we have extended the series of ribs for a portion of the circumference 95 only of each roller and have so constructed the other side of the roller that it will act on the stalk to feed it between the rollers, and as here shown we have provided a series of teeth 39 which are separated by relatively deep recesses and are arranged to engage the stalk and feed the same between the two rollers. The ear removing portions of the rollers may be of any suitable length but in Figs. 2, 3 and 5 we have shown these 100 portions of the rollers as relatively short and arranged to constitute intermediate portions of the rollers. The end portions of the rollers, on one or both sides of the ear removing portions thereof, are provided 105 with spiral ribs, or screws, as shown at 40, which are arranged to engage the butt end of an ear and move the stalk and the ear lengthwise to bring the ear into engagement with the ear removing portions of the rollers. Consequently, it is not necessary that the stalk should be accurately positioned 110 with relation to the snapping rollers but it is sufficient if the ear will engage any part of the snapping rollers.

Preferably the spiral ribs are also pro- 115

vided with recesses, as shown at 51 in Fig. 5, which are arranged in line with the spaces between the teeth 39 of the ear removing portions. The spaces between the 5 teeth 39, and the recesses in the spiral ribs, constitute longitudinally extending channels which receive the stalk of corn and prevent the same from being crushed as it passes between the rollers. The spiral ribs 10 in addition to moving the ear into contact with the ear removing portions of the rollers also serve to turn the ear so that it will extend transversely to the rollers, thus causing the butt only of the ear to be engaged 15 by the ear removing portions of the rollers and preventing almost entirely the shelling of the grains of corn from the ear by the rollers.

However, if desired, the corrugated positions of the snapping rollers may be extended for the full length of the rollers and the spirals omitted, as shown in Figs. 6 and 7.

In Fig. 8 we have shown another arrangement of snapping rollers in which the rollers, which are shown at 48, are eccentrically mounted, so that when in the position shown in the drawings sufficient space will be provided between them for the passage of a stalk of corn. The continued rotation of 30 the rollers will bring into operative positions the other portions of the rollers, which have longer radii, so that these portions may act upon the ear of corn to sever the same from the stalk. These rollers may have any suitable surface but, as here shown, they are corrugated throughout their circumferences.

In Fig. 9 we have shown still another arrangement of snapping rollers in which the rollers 49 and 50 are corrugated on one side 40 of their circumferences and have smooth surfaces on the other sides thereof. One of the rollers 49 has its smooth portion of a shorter radius than the corrugated portion while the other roller 50 has the corrugated 45 and smooth portions of the same radius. Consequently, when in the position shown in the drawings a space will be provided between the rollers for the passage of stalks of corn. It will be understood, however, 50 that, if desired, both rollers may have portions, either smooth or corrugated, of shorter radius, to correspond with the roller 49 and, further, that in that form of the rollers shown in Fig. 8 either one or both of the 55 rollers may be eccentric.

That portion of the shaft 35 lying between the snapping roller 34 and the gears 37 may be provided with a plurality of pin wheels 41 which engage the stalks of corn and assist in moving the same toward the edge of the platform. The transverse bar 26 must be supported in such a manner that the supports therefor will not interfere with the 60 passage of the stalks of corn along the platform 4 and, as here shown, it is supported at

one end, at the left hand end in Fig. 2, directly on the frame, but its other, or right hand, portion projects a considerable distance beyond the main frame and is supported at its outer end at such a point that 70 the support will not interfere with the passage of the corn stalks. Downwardly curved guard fingers 46 are secured to the rear edge of the platform 4 and serve to support the stalks of corn out of engagement with the 75 sprocket wheels as they are discharged from the platform.

The ears, as they are separated from the stalks, drop downwardly away from the snapping rollers and to facilitate this movement of the ears we prefer to set the upper snapping roller slightly in advance of the lower roller. The ears may be delivered from the snapping rollers at any desired point but in the present machine the platform 80 4 is provided at a point in the front of, and in line with, the snapping rollers with an opening 42, through which the ears drop into a chute 43 leading to the husking rollers 44. These husking rollers are driven from 85 the shaft 23 and slope forwardly so that the ears of corn will be fed toward the front end of the machine and delivered to the conveyor 45 which in turn will deliver them to the 90 wagon, or other point of delivery.

The operation of the mechanism will be readily understood from the foregoing description of the several parts thereof and it will be apparent that we have provided an 95 ear removing mechanism which is very simple in its construction and operation and which will feed the stalks of corn to the snapping rollers, properly position the same with relation thereto, remove the ears from the stalks without breaking the latter, deliver the stalks to a pile in front of the machine, and deliver the ears to the husking rollers.

While we have shown and described one embodiment of our invention, we wish it to be understood that we do not desire to be limited to the details thereof as various modifications may occur to a person skilled in the art.

Having now fully described our invention what we claim as new and desire to secure by Letters Patent, is:

1. In a machine of the character described, a supporting structure, a pair of snapping rollers carried by said structure, said structure and said rollers being arranged to permit a stalk of corn to pass between said rollers in a position substantially parallel therewith and to prevent the passage of an ear on said stalk, means to actuate said snapping rollers, said rollers having ear removing portions of less length than said rollers and also having other means to engage said ear and move said stalk lengthwise of said rollers to bring the ear into 115 120 125 130

engagement with the ear removing portions of said rollers.

2. In a machine of the character described, a supporting structure, a pair of snapping rollers carried by said structure, said structure and said rollers being arranged to permit a stalk of corn to pass between said rollers in a position substantially parallel therewith and to prevent the passage of an 10 ear of corn on said stalk, and means to actuate said snapping rollers, said rollers having ear removing portions spaced from the ends thereof and also having other means arranged at the ends of said ear removing 15 portions to engage the ear and move the stalk lengthwise of said rollers to bring the ear into engagement with the ear removing portions of said rollers.

3. In a machine of the character described, a pair of snapping rollers, means to present a stalk of corn to said rollers in a position substantially parallel therewith, said rollers being arranged to permit the passage of said stalk but to prevent the 20 passage of an ear of corn on said stalk, and means for actuating said snapping rollers, said rollers having intermediate ear removing portions and having at the opposite ends of said ear removing portions 25 spiral ribs arranged to engage the butt of said ear and impart lengthwise movement to said stalk to bring the ear into engagement with said ear removing portions of 30 said rollers.

35 4. In a machine of the character described, a pair of snapping rollers, means to present a stalk of corn to said rollers in a position substantially parallel therewith, said rollers being arranged to permit the 40 passage of said stalk but to prevent the passage of an ear of corn on said stalk, and means for actuating said snapping rollers, said rollers having ear removing portions and also having spiral ribs arranged to engage the butt of said ear and impart length- 45 wise movement to said stalk to bring the ear into engagement with the ear removing portions of said rollers.

5. In a machine of the character described, a pair of snapping rollers, means to present a stalk of corn to said rollers in a position substantially parallel therewith, said rollers being arranged to permit the 50 passage of said stalk but to prevent the passage of an ear of corn on said stalk, and means for actuating said snapping rollers, said rollers having ear removing portions and one of said rollers having a spiral rib arranged to engage the butt of said ear and 55 impart lengthwise movement to said stalk to bring the ear into engagement with said ear removing portion of said rollers.

6. In a machine of the character described, a pair of snapping rollers each having 60 an ear removing portion, means for

actuating said snapping rollers, a feeding device moving transversely to the axes of said snapping rollers to move stalks of corn transversely of their length toward said snapping rollers, said snapping rollers having means arranged at the opposite ends of the ear removing portions thereof and independent of said actuating means to move said stalks of corn lengthwise and to bring the ears thereon into engagement with said ear removing portions of said rollers.

7. In a machine of the character described, a pair of snapping rollers, means for presenting a stalk of corn to said rollers in a position substantially parallel therewith, said rollers being arranged to permit the passage of said stalk of corn without crushing the same, and one of said rollers having on one side thereof a part to feed the stalk between the rollers and having on the opposite side thereof a part to remove the ear from the stalk.

8. In a machine of the character described, a pair of snapping rollers, means for presenting a stalk of corn to said rollers in a position substantially parallel therewith, said rollers being arranged to permit the passage of said stalk of corn without crushing the same, and each of said rollers having on one side thereof a part to feed the stalk between the rollers and having on the opposite side thereof a part to remove the ear from the stalk.

9. In a machine of the character described, a pair of snapping rollers, means for presenting a stalk of corn to said rollers in a position substantially parallel therewith, said rollers being arranged to permit the passage of a stalk of corn without crushing the same, and one of said rollers having on one side thereof a circumferentially arranged series of longitudinal ribs and having on the opposite side thereof a plurality of teeth, said parts being so arranged that said teeth will feed the stalk of corn between the rollers without crushing it and said ribs will remove the ear from the stalk.

10. In a machine of the character described, a pair of snapping rollers each having on one side thereof a circumferentially arranged series of longitudinal ear removing ribs and having on the opposite side thereof means for feeding a stalk of corn between the rollers, means for presenting a stalk of corn to said snapping rollers in a position substantially parallel therewith, said rollers being so arranged relatively one to the other that said stalk will be moved between the rollers without crushing it and said ribs will remove the ear from the stalk.

11. In a machine of the character described, a pair of snapping rollers, means for rotating said rollers in opposite directions, a feeding device extending transversely to said snapping rollers and to a point near the

same, and means arranged at one end of one of said rollers and on the outer side of said feeding device to advance the end portions of the stalks as the intermediate portions thereof are fed between said rollers.

12. In a machine of the character described, a pair of snapping rollers, means for rotating said rollers in opposite directions, feeding chains moving transversely to the axes of said rollers to advance the stalks of corn thereto, and guides arranged above and substantially parallel with the respective chains to retain the stalks in engagement therewith.

13. In a machine of the character described, a pair of snapping rollers, means for rotating said rollers in opposite directions, feeding chains moving transversely to the axes of said rollers to advance the stalks of corn thereto, and arms arranged above and substantially parallel with the respective chains to retain the stalks in engagement therewith, and means acting on the stalks of corn as they approach said feeding chains to cause them to enter the space between said chains and said arms one at a time.

14. In a machine of the character described, a pair of snapping rollers, means for rotating said rollers in opposite directions, feeding chains moving transversely to the axes of said rollers to advance the stalks of corn thereto, arms arranged above and substantially parallel with the respective chains to retain the stalks in engagement therewith, a shaft journaled in said arms, pin wheels carried by said shaft, adjacent to the respective arms and arranged to engage the stalks of corn as they approach said arm, and means for rotating said shaft.

15. In a machine of the character described, a pair of snapping rollers arranged one above the other, means for rotating said rollers in opposite directions, stalk feeding chains moving transversely to the axes of said rollers, a transverse bar arranged above said feeding chains, bearings for the upper snapping roller carried by one side of said bar, arms secured to the other side of said bar and arranged substantially parallel to the respective chains to hold the stalks of corn in engagement therewith, and means arranged near the outer ends of said arms to move the stalks of corn between said chains and said arms.

16. In a machine of the character described, a main frame, a platform carried by said main frame, a transverse bar supported at one end of said main frame and having one end extending laterally beyond said main frame, a snapping roller journaled in bearings carried by said platform, a second snapping roller journaled in bearings carried by said transverse bar, a feeding de-

vice arranged between said platform and said transverse bar and moving transversely to the axes of said snapping rollers, and means for rotating said snapping rollers in opposite directions.

17. In a machine of the character described, a main frame, a platform carried by said main frame, a transverse bar supported at one end of said main frame and having one end extending laterally beyond said main frame, a snapping roller journaled in bearings carried by said platform, a second snapping roller journaled in bearings carried by said transverse bar, a feeding device arranged between said platform and said transverse bar and moving transversely to the axes of said snapping rollers, means for rotating said snapping rollers in opposite directions, said last mentioned snapping rollers comprising a shaft extending beyond the end thereof, and pin wheels carried by said shaft.

18. In a machine of the character described, a substantially horizontal platform, a pair of snapping rollers arranged with their axes in substantially horizontal planes near one edge of said platform, feeding devices movable over said platform and transversely to said axes of said snapping rollers to move stalks of corn toward the same, means cooperating with said devices to hold the stalks of corn in operative engagement therewith, an inclined platform arranged to receive stalks of corn from the shock, and a feeding device movable over said inclined platform to move the stalks of corn toward said horizontal platform.

19. A snapping roller comprising an intermediate portion having longitudinally extending ribs on one side thereof and stalk feeding teeth on the other side thereof, and having spiral ribs on both end portions thereof to engage the ear and feed the stalk lengthwise to cause the ear to be engaged by said intermediate portion thereof.

20. In a machine of the character described, a pair of snapping rollers, each having an ear removing portion, means to actuate said snapping rollers, a feeding device moving transversely to the axes of said snapping rollers to move stalks of corn transversely of their lengths toward said snapping rollers, said snapping rollers having means arranged at one end of the ear removing portions thereof to move said stalks of corn lengthwise to bring the ears thereon into engagement with said ear removing portions of said snapping rollers.

21. In a machine of the character described, a pair of snapping rollers, each having an ear removing portion, means to actuate said snapping rollers, a feeding device moving transversely to the axes of said snapping rollers to move stalks of corn transversely of their lengths toward said snap-

- ping rollers, said snapping rollers having spiral ribs arranged at one end of the ear removing portions thereof to engage the ears and move said stalks of corn lengthwise 5 to bring said ears into engagement with said ear removing portions of said snapping rollers.
22. In a machine of the character described, a pair of snapping rollers, each having an ear removing portion, means to actuate said snapping rollers, a feeding device moving transversely to the axes of said snapping rollers to move stalks of corn transversely of their lengths toward said snapping rollers, said snapping rollers having spiral ribs arranged at both ends of the ear removing portions thereof to engage the ears and move said stalks of corn lengthwise to bring 10 said ears into engagement with said ear removing portions of said snapping rollers.
23. In a machine of the character described, a pair of snapping rollers and means for presenting a stalk of corn to said rollers in a position substantially parallel therewith, said snapping rollers being so shaped and arranged with relation one to the other that during a portion of the rotation of 15 said rollers their adjacent surfaces will be spaced apart to permit of the passage of a stalk of corn extending lengthwise thereof, and during another portion of their rotation the adjacent surfaces will be arranged close together to snap an ear of corn from 20 said stalk.
24. In a machine of the character described, a pair of snapping rollers, each having a portion of its surface corrugated, and means for presenting a stalk of corn to said snapping rollers in a position substantially parallel therewith, said rollers being so arranged that when said corrugated 25 portions of said rollers are adjacent one to the other they will engage the stem of an ear of corn and sever the ear from the stalk, said rollers having other portions so arranged that when adjacent one to the other they will be spaced a substantial distance apart, thereby permitting the stalk to pass 30 between the rollers without being crushed, and removing the ears therefrom.
25. In a machine of the character described, a pair of snapping rollers, each having a corrugated portion, means for presenting a stalk of corn to said snapping 35 rollers in a position substantially parallel therewith, the two rollers being so arranged that when said corrugated portions are adjacent one to the other they will sever an ear of corn from the stalk, one of said rollers having another portion of shorter radius 40 than the corrugated portion thereof so that when said last mentioned portion is adjacent to the other roller a space will be provided between the two rollers for the passage 45 of a stalk of corn.
26. In a machine of the character described, a feeding table, a pair of snapping rollers arranged substantially parallel to the feeding table, and means for presenting a stalk of corn to said snapping rollers in a position substantially parallel therewith, said rollers being so constructed and arranged that when in one position a space 50 will be provided between said rollers to permit said stalk of corn to pass between them parallel with their axes and when in another position the adjacent surfaces of said rollers will engage an ear of corn and remove the same from said stalk, said feeding table having an opening to permit the ear of corn thus separated from the stalk to pass away from the rollers.
27. In a machine of the character described, a feeding table, a pair of snapping rollers arranged substantially parallel with 55 said table, and means to present a stalk of corn to said snapping rollers in a position substantially parallel therewith, said rollers being so constructed and arranged that when in one position a space will be provided between said rollers to permit a stalk of corn to pass between them parallel with their axes and when in another position the adjacent surfaces of said rollers will engage an ear of corn and remove the same from said stalk, said feeding table having an opening to permit the ear of corn thus separated from the stalk to pass away from the rollers.
28. In a machine of the character described, a pair of snapping rollers, and means for presenting a stalk of corn to said rollers in a position substantially parallel therewith, one of said snapping rollers having a longitudinal recess in one side thereof to receive the stalk of corn and permit the same to pass between the rollers without being crushed.
29. In a machine of the character described, a pair of snapping rollers, and means for presenting a stalk of corn to said rollers in a position substantially parallel therewith, one of said snapping rollers having a longitudinal recess in one side thereof to receive the stalk of corn and permit the same to pass between the rollers without being crushed, said rollers having means to remove the ears of corn from the stalks after the stalks have passed between the rollers.
30. In a machine of the character described, a pair of snapping rollers, and means for presenting a stalk of corn to one of said rollers in a position substantially parallel therewith, said rollers having corresponding peripheral portions so shaped and arranged as to provide a space between said rollers when said portions are adjacent one to the other, said space being adapted to receive a stalk of corn and permit the same to pass between said rollers.

without being crushed, and said rollers also having their peripheral portions arranged to sever an ear from said stalk after the latter has entered said space.

5 31. In a machine of the character described, a pair of snapping rollers, means for presenting a stalk of corn to said rollers in a position substantially parallel therewith, one of said snapping rollers having a 10 longitudinal recess in one side thereof to receive the stalk of corn and permit the same to pass between the rollers without being crushed, and having a spiral rib to move the stalk lengthwise of said rollers to bring 15 the ear into contact with the ear removing portions thereof.

32. In a machine of the character described, a pair of snapping rollers, a conveyor to move stalks of corn between said 20 rollers in a position substantially parallel therewith and to discharge said stalks at a point beyond said rollers, and a guard to receive said stalks as they approach said point of discharge and cause them to be 25 moved out of engagement with said conveyor.

33. In a mechanism of the character described, a pair of snapping rollers, a conveyor to move stalks of corn between said 30 rollers in a position substantially parallel therewith and to discharge said stalks at a point beyond said rollers, and a guard having one end supported adjacent to and substantially in the plane of said conveyor and 35 having its other end extending downwardly beyond the point of discharge of said conveyor.

34. In a machine of the character described, a pair of snapping rollers, sprocket 40 wheels arranged on opposite sides of said snapping rollers, feed chains carried by said sprocket wheels and having their upper stretches extending between the axes of said rollers, and guards arranged on the 45 discharge side of said rollers in a position to receive the stalks of corn as they approach the ends of said feed chains, said guards having downwardly turned end por-

tions arranged beyond the discharge ends of said feed chains. 50

35. In a machine of the character described, a supporting structure, and a pair of snapping rollers carried by said structure, said structure and said rollers being arranged to permit a stalk of corn to pass 55 between said rollers in a position substantially parallel therewith and to prevent the passage of an ear of corn on said stalk, said rollers having ear removing portions of less length than said rollers and also having 60 means to engage said ear and move said stalk lengthwise of said rollers to bring the ear into engagement with the ear removing portions of said rollers, and to turn said ear 65 to a position in which it will extend transversely to said rollers.

36. In a machine of the character described, a supporting structure, and a pair of snapping rollers carried by said structure, said structure and said rollers being 70 arranged to permit a stalk of corn to pass between said rollers in a position substantially parallel therewith and to prevent the passage of an ear of corn on said stalk, said rollers having ear removing portions and 75 also having means to turn said ear of corn to a position in which it will extend transversely to said rollers.

37. In a machine of the character described, a supporting structure, a pair of 80 snapping rollers mounted on said structure and arranged to permit a stalk of corn to pass between the same in a position parallel therewith, conveyors mounted on said structure for moving a stalk of corn transversely 85 to its length into engagement with said snapping rollers, said rollers having means to remove an ear from the stalk, and means for rotating said snapping rollers in opposite directions and for driving said conveyors. 90

In testimony whereof, we affix our signatures hereto.

SAMUEL E. MORRALL,
WILLIAM W. MORRALL.
